SOCK PACKAGE

Otto Hass, Jr., Charlotte, N.C., assignor to Weyerhaeuser Company, Tacoma, Wash., a corporation of Washington
Original application Dec. 27, 1960, Ser. No. 78,418.
Divided and this application Feb. 23, 1962, Ser. No.
175,174

2 Claims. (Cl. 206—46)

This invention relates to a novel article package and 10 specifically relates to a hosiery package.

As was stated in application Serial Number 78,418, filed December 27, 1960, of which this application is a division, it is preferable that a backing insert for items such as socks be economical, and be of a construction 15 that allows easy placement of the socks thereon.

It is therefore an object of this invention to provide a new and novel insert which is economical to produce and which is economical to use.

It is also an object of this invention to provide a 20 new and novel insert upon which items may be quickly and easily placed.

It is another object of this invention to provide a novel and economical article package in which the articles are quickly and easily placed on a backing sheet 25 that allows them to be displayed.

It is a further object of this invention to provide a novel and economical hosiery package in which the articles are placed on a simple backing sheet which allows 30 the display of the hosiery.

These and other objects of this invention will become 35 apparent from the following discussion of the drawings in which:

FIGURE 1 is a top plan view of a blank for the insert.

FIGURES 2-5 are isometric views of the insert during various stages of the operation of placing a pair of socks thereon.

FIGURE 6 is an isometric view of the package.

The numeral 50 broadly indicates the article insert 40 or backing sheet. The insert is trapezoidal in shape and is defined by side edges 51 and 52, and first and second end edges 53 and 54. The second end edge 54 is placed diagonally of the side edges 51 and 52 so that the leg portion of a sock wrapped around the insert will 45

2

overlay the foot portion. Adjacent the first end edge 53 is an insert flap 55 which is defined by curvilinear edges 56 and 57, a bottom edge 58, and an upper fold line 59.

5 In use, as may be seen in FIGURES 2-5, the flap 55 is folded upwardly and the elastic band of one sock 61 of a pair of socks is dropped through the aperture 60 formed in insert 50 by flap 55. The elastic band of the second sock 62 is placed on the flap 55 and the socks are draped around the insert. The insert is then placed in an envelope or container 90 to form package 100.

It should be understood that the above description and drawings are by way of illustration and not limitation, and that the structure can be changed and modified in various ways without departing from the scope of the invention as hereafter claimed.

I claim:

1. An article package, comprising:
a trapezoidal-shaped insert having first and second end edges and side edges;
said second end edge being diagonal to said side edges;
a flap hingedly connected to said insert adjacent said first end defining an aperture through said insert;
said flap having curvilinear side edges;
a first article extending through said aperture and draped around said insert and said second diagonal end edge;
a second article placed around said flap and draped around said insert and said second diagonal end edge;
said second article being contiguous with said first article;
a cover around said insert and said articles.
2. The article package of claim 1 in which said articles are socks.
